UNITED STATES PATENT OFFICE.

JAMES G. MACLAUREN, OF SYRACUSE, NEW YORK, ASSIGNOR TO THE LAMSON COMPANY, OF SYRACUSE, NEW YORK, A CORPORATION OF MASSACHUSETTS.

ASSORTING APPARATUS FOR CONVEYER SYSTEMS.

Application filed February 21, 1925. Serial No. 10,833.

To all whom it may concern:

Be it known that I, JAMES G. MACLAUREN, a citizen of the United States of America, and resident of Syracuse, in the county of 5 Onondaga and State of New York, have invented new and useful Improvements in Assorting Apparatus for Conveyer Systems, of which the following is a specification.

This invention pertains to conveyer systems and more particularly to selecting or assorting apparatus for separating articles of different classes, while in transit over the conveyer system, into groups in accordance with their respective classes.

15 The principal object of the present invention is to provide a selecting or assorting apparatus of extremely simple form and construction, yet withal rugged and durable and capable in a thoroughly reliable manner 20 of assorting moving articles in accordance with the configurations of their advancing ends.

For purposes of illustration I have chosen 25 to describe my invention as embodied in a pneumatic despatch system wherein "carriers" are moved by air pressure through a transmission tube, such carriers being divided into classes having heads of different configuration. For example the heads of 30 one class may be flat and those of another class may be provided with central recesses, in accordance with the particular kind of transaction for which they are designed.

35 In the accompanying drawings I have illustrated a preferred embodiment of the invention by way of example, and in such drawings,

Fig. 1 is a side elevation of the improved 40 selector;

Fig. 2 is a vertical section through the selector, showing in dotted lines a carrier with recessed head at the instant of its engagement with the selector mechanism and 45 also at a later stage in the operation;

Fig. 3 is a section substantially on the line 3-3 of Fig. 2; and

Fig. 4 is a section similar to Fig. 2 but illustrating the action of a flat-headed carrier in passing through the selecting mechanism.

50 My improved selector comprises a housing 50 of tubular form having flanges 50^a and 50^b at its upper and lower ends respectively providing convenient means for at-

taching it to the end of a tube section or sections, for example the section 50^c. This housing is provided intermediate its ends with a lateral delivery opening 40 preferably guarded upon opposite sides by substantially parallel wings 41 and 42 respectively. The housing 50 is also furnished with a vertical slot 43 diametrically opposite to the opening 40 and preferably arranged with its upper end slightly above the plane 65 of the lower edge of the opening 40.

A combined detector and abutment designated by the numeral 51, normally projects inwardly through the slot 40 into the path of carriers moving longitudinally through 70 the housing 50. This abutment terminates at its inner end in a projection or detector finger 52 normally disposed substantially at the axis to the carrier path and projecting above the straight and normally horizontal 75 upper edge of the body of the abutment to a distance slightly less than the depth of the recess in the head of a recessed carrier.

The abutment 51 is pivoted at 51^a between the upper ends of a pair of parallel legs 53 80 which in turn are pivoted to a pin 54 supported by a pair of ears 55 projecting from the housing 50 near the lower end of the slot 43. The abutment 51 and the legs 53 are normally retained in the position shown 85 in Fig. 2 by means of a spring 56 or equivalent device.

At the upper, outer end of the abutment 51 a projection 57 is provided which normally engages the outer surface of the housing 50. A pin 58 sufficiently long to engage the rear edges of the legs 53 projects from the opposite sides of the abutment 51 at its lower end. With this arrangement the spring 56 tends to hold the projection 57 95 against the outer surface of the housing 50 with the pin 58 bearing against the legs 53, thus retaining the abutment 51 in carrier receiving position.

When a carrier having a recessed head 100 encounters the abutment 51 the latter remains substantially in its normal position, as the force of the blow of the rim of the carrier is applied directly over the pivot 51^a, and as the point of contact of the carrier with the abutment is between the projection 52 and the inner wall of the tube, and to one side of the center of gravity of the carrier, the latter is caused to tip sidewise out through 105 the opening 40 as indicated in dotted lines 110

at 69. On the other hand a carrier 70 having a flat or other suitably shaped head will strike the detector projection 52 of the abutment and will thus revolve the latter 5 about its pivot 51^a, and because the projection 57 is in engagement with the outer wall of the housing 50 the abutment 51 will move bodily from out of the tube into the position shown in Fig. 4, thus permitting such a flat-headed carrier 70 to continue on through the housing and into the distributing terminal.

The device thus provided is of exceedingly simple form and yet performs its function with all desired speed and accuracy. 15 As no latches or other locking means are used there is little chance for the parts to jam or stick, while the cost of production, as compared with prior devices of more 20 complex character, is very low.

Although I have shown and described one specific embodiment of the invention I wish it to be understood that the exact shapes and proportions of parts herein disclosed 25 are not necessarily essential but that various changes, rearrangements and substitutions may be made without departing from the spirit of the invention.

I claim:

1. A carrier sorting device for carrier despatch systems comprising a tube for directing carriers, an abutment normally projecting into the tube, and means for pivotally supporting the abutment, said abutment being so shaped that carriers of one kind engage it at a point substantially in the vertical plane of its fulcrum and carriers of another kind engage it at a point laterally removed from its fulcrum.
2. A carrier sorting device for carrier despatch systems comprising a tube for directing carriers, an abutment normally projecting into the tube, and a movable fulcrum for the abutment, the abutment being so shaped that carriers of one type engage it at a point adjacent to the axis of the tube and that other carriers engage it at a point intermediate the axis and the wall of the tube.
3. A sorting device for carrier despatch systems comprising a tube for directing carriers, an abutment normally projecting into the path of carriers moving through the tube, and movable means for pivotally supporting the abutment, the abutment being so shaped that carriers of one configuration engage it at a point further from its fulcrum than carriers of another configuration, and means constraining said abutment to move bodily from out of the tube when engaged by carriers of the first kind.

4. A sorting device for carrier despatch systems comprising a tube for directing carriers, an abutment normally projecting into the path of carriers moving along the tube, a supporting fulcrum for the abutment mov-

able toward and from the axis of the tube, and means tending to retain the abutment and its fulcrum in normal position.

5. A carrier sorting device for separating carriers having centrally recessed heads 70 from carriers of another kind comprising a tube for directing carriers, an abutment having an upwardly directed detector finger normally disposed substantially axially of the tube, a movable support for the abutment, said abutment being substantially immovable when a carrier engages it at a point intermediate its finger and the wall of the tube and moving bodily from out of the tube when a carrier engages the end of said 80 finger.

6. A carrier sorting device for separating carriers having recessed heads from other types of carriers comprising a carrier guiding tube and an abutment normally projecting into the tube and terminating in a projecting detector finger disposed substantially axially of the tube and directed toward approaching carriers, the finger being spaced from the wall of the tube, a stop 90 carried by the abutment engaging the outer wall of the tube, and means pivotally supporting the abutment to swing about an axis such that when engaged by a carrier having a recessed head the abutment remains substantially in normal position whereby the energy of translation of the carrier is converted into energy of rotation about its point of engagement with the abutment as a center.

7. A sorting device for carrier despatch systems comprising an abutment normally projecting into the path of the carriers, a fulcrum for said abutment normally positioned within said path but movable laterally therefrom, means tending to move the fulcrum into said path, and means for limiting such movement.

8. A sorting device for carrier despatch systems comprising an abutment having a detector member normally disposed substantially at the central axis of the path of travel of the carriers and having a stop element positioned outside of said path, a fulcrum for the abutment intermediate said detector member and stop element, a spring tending to swing the fulcrum inwardly across said path, and a fixed member engaging said stop element.

9. A sorting device for carrier despatch systems comprising a tube for directing carriers, an abutment projecting into the tube through an opening in the wall of the latter, a movable fulcrum for the abutment normally positioned inside the tube, and a stop member upon the abutment engaging the outer surface of the wall of the tube.

10. A sorting device for carrier despatch systems comprising a tube for directing carriers, said tube having an opening in its side 130

wall, an abutment projecting into the tube through said opening, said abutment having a detector finger normally disposed adjacent to the axis of the tube and a stop lug engaging the outer surface of the tube, a fulcrum for the abutment at a point intermediate said finger and lug, and a pivotally supported lever carrying said fulcrum.

11. A sorting device for carrier despatch systems comprising a tube for directing carriers, said tube having a longitudinally disposed slot in its side wall, an abutment projecting into the tube through the upper part of such slot, a lever pivoted at its lower end near the bottom of the slot, a fulcrum for the abutment adjacent to the upper end of the lever, said fulcrum normally being disposed inside the tube, stop means to limit inward movement of said fulcrum, and a detector finger projecting from the abutment in position to be engaged by carriers of a certain class thereby to move the abutment bodily out through the slot in the tube.

12. A sorting device for carrier despatch systems comprising a tube for directing carriers, an abutment projecting into the tube through an opening in the wall of the latter, said abutment having a detector finger normally disposed adjacent to the axis of the tube and a stop lug engaging the outer surface of the tube, a movable fulcrum for the abutment disposed substantially midway between the detector finger and stop lug, and a spring tending to move said fulcrum toward the axis of the tube.

13. A sorting device for carrier despatch systems comprising a tube for directing car-

riers, an abutment projecting into the tube through an opening in the wall of the latter, said abutment having a detector finger normally disposed adjacent to the axis of the tube and a stop lug engaging the outer surface of the tube, a lever pivotally secured at one end to the abutment at a point intermediate the detector finger and stop lug, said lever being pivotally mounted at its opposite end at a point adjacent to the wall of the tube, and a stop carried by the abutment and normally engaging the lever at a point intermediate the ends of the latter.

14. A sorting device for carrier despatch systems comprising a tube for directing carriers, said tube having an elongate longitudinal slot in its wall, an abutment disposed adjacent to the upper end of said slot, the abutment projecting into the tube and having a detector finger at its inner end normally disposed adjacent to the axis of the tube, a stop finger at the outer end of the abutment engaging the outer surface of the tube, a lever pivoted at one end near the lower end of the slot, a fulcrum pin connecting the opposite end of the lever to the abutment at a point intermediate the detector finger and stop lug, a spring tending to swing the upper end of the lever toward the axis of the tube, and a stop pin carried by the abutment and engaging the outer edge of the lever at a point substantially midway between the ends of the latter.

Signed by me at Syracuse, New York, this 19th day of February, 1925.

JAMES G. MACLAREN.
